UNITED STATES PATENT OFFICE.

WILLIAM J. NEUKOM, OF INDIANAPOLIS, INDIANA.

DESIGN FOR A CHAIR.

SPECIFICATION forming part of Design No. 35,112, dated September 17, 1901.

Application filed April 20, 1901. Serial No. 56,783. Term of patent 3½ years.

To all whom it may concern:

Be it known that I, WILLIAM J. NEUKOM, a citizen of the United States, residing at Indianapolis, in the county of Marion and State 5 of Indiana, have invented and produced a new and original Design for Chairs, of which the following is a specification.

The accompanying drawing illustrates my design.

10 The drawing is a perspective view of a chair embodying my design.

The essential feature of my design consists of the seat 4, which connects the bases of a pair of U-shaped bars 5 and 6, the U 5 being

shorter than U 6, with arm-rests 7 secured to 15 the upper ends thereof and extending to about the middle of the arms of U 6. The upper ends of the U 6 form a support for the upper end of a back 8.

The seat portion of the chair just described 20 is supported by suitable legs, as shown.

I claim as my invention—

The design for a chair substantially as shown and described.

WILLIAM J. NEUKOM.
